METHOD OF AND ARRANGEMENT FOR RECEIVING SHORT WAVES

Manfred von Ardenne, Berlin, Germany

Original application February 5, 1934, Serial No. 709,707. Divided and this application April 15, 1936, Serial No. 74,441. In Germany February 15, 1933

3 Claims. (Cl. 250—27)

The present invention relates to an electronic tube for rectifying short waves and is a division of application, Serial No. 709,707, filed February 5, 1934.

- 5 In the construction of receiving apparatus for short waves, more particularly for waves of less than 10 meters, it has been found that a satisfactory sensitiveness of the rectification cannot be obtained when using anode bend rectification. 10 The order of magnitude of the rectifying effect amounted in this connection to merely approximately 10% of that particular value caused by the same control potential when normal radio waves are rectified. 15 By careful investigation of the frequency dependency of the efficiency of the rectifier the applicant has been able to ascertain the reasons for the low efficiency not occurring in the normal radio frequency range, and to find means for 20 remedying the same.

Experiments of this nature may be conducted in such fashion that one and the same high-frequency amplitude is conducted to a tube rectifying connection system at a frequency varied 25 between $\lambda=3$ meters and 200 meters, the potential rectifying effect is measured in the anode circuit. By such measurements the applicant has found that the rectification of short waves is considerably better if relatively powerful currents are effected in the rectifier circuits. According to the invention, this is effected by employing small resistances in the anode circuit. 30

Experiments have provided the following results:

- 35 In the range of the frequencies below a wave length of 30 meters the sensitiveness decreases in the case of anode bend rectification with the use of grid leakage resistances in the usual order of 10^6 ohms and reaches the relatively lowest value 40 at 7 meters. Also in the case of anode bend rectification with high anode resistances of approximately 500,000 ohms there is a decrease in the sensitiveness in the case of waves below approximately 20 meters. Now a considerably better effect may be obtained in accordance with the invention by operating in the case of anode bend rectification with anode resistances which are considerably smaller than those employed with 45 good results for normal frequency. 50 The electrons which in the case of anode bend rectification with high anode resistances form the anode current possess speeds which are usually very low, the control potential possessing a value in the order of approximately 1 volt. The 55 electrons do not assume higher speeds until the

electrons have passed the grid, i. e. at a time when control has already taken place. As long as the electron speeds are so small, the time in which an electron is passing from cathode to anode is such that the same is greater, or may be greater, than the period, for example, of a 7-meter oscillation. From the influence exerted by the duration of passage of the electrons, which cannot be ignored in rectification, there results the frequency dependency of the rectification in the frequency range above stated. 10

After having found out the reasons for this frequency dependency in accordance with the invention for improving the efficiency of the anode-bend rectification for short waves there is used a relatively small anode resistance in the order of 10^4 ohms, which causes the full anode potential to be applied to the anode practically continuously; further, tubes having a relatively small amplifying factor $\alpha=10$ are used. In this connection the resting or working point is transferred as far as possible near to or in the upper bend in the characteristic of the anode current. The object of the arrangement according to the invention is to perform the control in such fashion by the high-frequency potential to be rectified that electrons having as far as possible a high speed are covered by the control, and that the control takes place in a narrowly confined space surrounding the grid. 20 25 30

When employing connection systems having resistances with the value and arrangement as set forth in accordance with the invention it is possible to produce receivers for short waves, and more particularly waves of less than 10 meters (preferably for television purposes), which have an adequate sensitiveness, even without intermediate frequency. 35

In the drawing there is shown by way of an example a form of embodiment of receiving and rectifying systems for anode-band rectification, the connecting elements in the working circuits having the values according to the invention. The single parts are the rectifier tube 1 with the cathode 2, the grid 3 and the anode 4. 40 45

Between the grid and the cathode there is provided the oscillatory circuit 5, which comprises the self-inductance 6 and the variable capacity 7.

In the outer anode circuit there is connected a resistance 11 which, in accordance with the invention, is in the order of 10^4 ohms. Coupling is performed through the medium of a condenser 12. To accomplish a transfer of the working point to the upper bend of the characteristic 50 55

of the anode current there is provided the grid bias battery 10.

I claim:

- 5 1. In a tube for rectifying short waves, more particularly for waves of less than 10 meters, using anode bend rectification, a cathode, a grid and an anode, said anode connected to a source of high positive potential over a relatively small anode resistance, said tube having a small amplification factor, the anode potential being sufficient to make the time the electrons take to pass the distance between the electrodes shorter than a period of the high frequency to be rectified.
- 10 2. In a tube for rectifying short waves, more particularly for waves of less than 10 meters, using anode bend rectification, a cathode, a grid and an anode, said anode connected to a source of high positive potential over a relatively small anode resistance, said tube having an amplification factor smaller than 10, the anode potential being sufficient to make the time electrons take to pass the distance between the electrodes shorter than a period of the high frequency to be rectified.
- 15 3. In a tube for rectifying short waves, more particularly for waves of less than 10 meters, using anode bend rectification, a cathode, a grid and an anode, said anode connected to a source of high positive potential over a relatively small anode resistance, said tube having a small amplification factor, the anode potential being sufficient to make the time the electrons take to pass the distance between the electrodes shorter than a period of the high frequency to be rectified, a high positive grid bias sufficient to obtain a working-point in the upper end of the plate current-grid voltage characteristic.

MANFRED VON ARDENNE.
